UNITED STATES PATENT OFFICE.

HAROLD I. STAGE, OF SAN FRANCISCO, CALIFORNIA, ASSIGNOR TO INGERSOLL-RAND COMPANY, OF JERSEY CITY, NEW JERSEY, A CORPORATION OF NEW JERSEY.

SHOVELING AND LOADING MACHINE.

Application filed April 11, 1925. Serial No. 22,243.

To all whom it may concern:

Be it known that I, HAROLD I. STAGE, a citizen of the United States, and a resident of San Francisco, county of San Francisco, State of California, have invented a certain Shoveling and Loading Machine, of which the following is a specification accompanied by drawings.

This invention relates to shoveling and loading apparatus and more particularly to that type of shoveling machine which is adapted to handle large quantities of material in places where comparatively little head room is provided.

An object of the invention is to hold the shovel and to carry it back to its dumping position by means of a mechanism requiring comparatively little power to operate and which, in carrying the shovel back to its dumping position, keeps the shovel relatively low.

Another object of the invention is to construct such a machine simply, cheaply and with few controls so that it may be easily operated.

Other objects and advantages of this invention will be in part obvious and in part pointed out hereinafter.

Accordingly, the invention consists in the features of construction, combination of elements and arrangement of parts which will be exemplified in the construction hereinafter set forth, the scope of the application of which will be indicated in the appended claims.

The drawing illustrates one form which the invention may assume in practice and includes,

Figure 1, a vertical longitudinal section through the machine showing the internal arrangement of parts for operating the shovel;

Figure 2, a plan view of the machine, portions being broken away to more clearly show the cooperation of parts; and

Figure 3 is a side elevation of the machine showing more particularly the adjustability of the machine as to its height.

Referring to the drawings the machine includes a reciprocating frame A upon which are mounted side chains B for supporting and carrying a shovel C from a shoveling position on the forward end of

the machine as shown in Figure 1 to a rearward position at which the shovel C is 55 adapted to dump material into a suitable mine car D or other receptacle.

The chains B pass around rear sprockets E and front sprockets F and are guided intermediate the sprockets by flanges G which 60 may be formed integrally with housings H inclosing the chains and sprockets at the sides, Figure 3. The housings H also maintain proper spacing between the shaft J supporting the rear sprocket E and the shaft 65 K supporting the front sprocket F.

The shovel C is pivotally mounted on the chains B and to this end the shovel is provided with a pair of brackets L which are pivotally mounted by means of pins O on blocks P formed on two of the side links of the chain B. Each bracket L is provided with a rearwardly extending arm Q having at its end a roller R which is adapted to lie on the chain B while the shovel is travelling 75 backward to its dumping position. On the front of the bracket L there is provided a pin S to ride on a shoe T attached to the chain B. The roller R, pivot O and the pin S are in alignment so that on the straight 80 run of the chain B they hold the shovel C against tilting in either direction. As the shovel C passes over the front sprocket F, it turns about the pivot O and the pins S at front end of the shovel rest on the shoes T. This brings the shovel C to a convenient 85 position for loading. When the shovel is brought back to its dumping position, the rollers R are adapted to follow guides U 90 preferably formed integrally with the housings H. This tilts the shovel C upwardly 95 so that the pins S leave the shoes T, causing the material therein to slide out into the car D.

The chain B is operated by power applied to certain of the sprockets preferably the rear sprocket E and for other purposes any suitable type of power may be employed such as the flat piston air motor V mounted on a bracket W integral with the housings H. The motor V is provided with a drive shaft X having a worm Y meshing with a worm wheel Z on the shaft J. The shaft X and the worm wheel Z are preferably inclosed in a gear case b which also supports 100 bearings c for the shaft X. The motor V 105

should be reversible and to this end there is provided a three-way valve *d* to control the motor through flexible pipes *e* and *f* and to connect the latter with supply and exhaust passages *g* and *h* respectively. For manual control of the valve *d* a hand lever *j* is provided extending from the side of the machine (Figure 3).

Means are provided by which the head of the rear end of the frame may be adjusted so that the shovel *C* may dump its load into a high-sided car, as for instance *D'* (Figure 3). To this end a stationary bracket *k* having an arcuate slot *o* is adapted to cooperate with bolts *p* fixed on the outside of each of the housings *H*. Upon loosening the nut of the bolt *p* the rear end of the housings *H* may be lifted or oscillated about the shaft *K* and thereafter clamped at the desired heights by retightening the nuts of the bolts *p*.

In addition to the movements of the shovel *C* backward and forward between its loading and dumping positions, the shovel is adapted to be reciprocated to drive it into the pile of material to be removed and to this end means are provided to reciprocate the frame *A* with respect to a pivoted platform *q* resting on a base *r*. This means comprises a cylinder *s* mounted on the platform *q* and provided with a piston *t* having a piston rod *u* attached by means of a clamp *v* to the axle *K* of the forward sprockets *F*. The side beams *w* of the frame *A* form guideways for rollers *x* mounted on the cylinder *s*. Brackets *k* are mounted on the side beams *w* to rigidly support the housings *H*. A suitable motive fluid such as compressed air may be employed to actuate the piston *t* and to this end a three-way valve *y* is adapted to control the admission of motive fluid from the supply passage *g* into a passage *z* leading to the rear end of the cylinder *s*, or a passage *2* leading to the front end of the cylinder. The valve *y* is adapted to connect only one of these passages *z* and *2* with motive fluid at any one time and when one of these passages is open to the fluid supply, the other is open to exhaust through the passage *3* leading to atmosphere. For controlling the valve *Y* a hand operated lever *4* is provided extending at the side of the machine preferably adjacent the lever *j* (Figure 3) for the convenience of the operator.

The platform *q* is adapted to swing about a rearward pivot *5* so as to change the direction in which the shovel points in its position for loading without substantial change in its dumping position. An arcuate plate *6* formed integrally with the platform *q* and adapted to pivot about the pin *5* is adapted to slide on rollers *7* mounted on the base *r* having a similarly arcuate portion *8* beneath the plate *6*. Means for swinging the plat-

form *q* is provided by a rack *9* on the portion *8* and a pinion *10* on the plate *6*. The pinion *10* is manually operated by a handle *11* on a shaft *12* provided with a bevel pinion *13* meshing with a bevel gear *14* on the shaft *15* to which the pinion *10* is attached. The bearings *16* and *17* of the shaft *12* are mounted on the cylinder *s* and the shaft *12* is adapted to extend out to the side of the machine preferably near the levers *j* and *4* for the convenience of the operator.

The base *r* may be of any convenient form. If desired, it may rest on wheels on the rails *18* or, as shown in the drawing, may be arranged to slide thereon. In order to clamp the base *r* in position, there is provided a bar *19* supporting the base *r* at the pivot *5* and extending across the rails *18*. At one end of the bar *19* there are provided two clamping jaws *20* which, when the bar is turned about the pivot *5*, are adapted to clamp one of the rails *18* at its bead. If the base *B* were forced backwardly its tendency is to turn the bar *19* still farther to clamp the latter more firmly on the rail. At the forward end of the base *r* there are provided teeth *21* which are disposed between the rails *18* and project downwardly so as to engage one of the ties *22* upon which the rails *18* are supported. The base *r* is triangular in shape and therefore provides a three-point suspension for the machine resting directly on the rails at the forward end and at the pivot *5* on the bar *19* at the rear. Irregularities in the laying of the rails *18* therefore do not affect the stability of the machine.

I claim:

1. A shoveling and loading machine comprising a reciprocatory frame, front and rear sprockets mounted on said frame, chains adapted to be guided by said sprockets, a shovel supported by said chains and adapted to be carried thereby between a forward shoveling position and a rearward dumping position, and means for rocking the rear sprocket about the front sprocket for adjusting the dumping position of the shovel to suit varying conditions.

2. A shoveling and loading machine comprising a reciprocatory frame, front and rear sprockets mounted on said frame, chains adapted to be guided by said sprockets, a shovel pivotally supported on said chains and adapted to be carried thereby between a forward shoveling position and a rearward dumping position, and means for rocking the rear sprocket about the front sprocket for adjusting the dumping position of the shovel to suit varying conditions.

3. A shoveling and loading machine comprising a reciprocatory frame, front and rear sprockets mounted on said frame, chains adapted to be guided by said sprockets, a shovel pivotally supported by

- 5 said chains and adapted to pass over said front and rear sprockets with said chains to be tilted downwardly and upwardly, and means for rocking the rear sprocket about the front sprocket for adjusting the dumping position of the shovel to suit varying conditions. 6 70
- 10 4. A shoveling and loading machine comprising a reciprocatory frame, front and rear sprockets mounted on said frame, chains adapted to be guided by said sprockets, means to actuate said chains, a shovel pivotally supported on said chains and arranged to pass over said front and rear sprockets with said chains to be tilted downwardly and upwardly, and means for rocking the rear sprocket about the front sprocket for adjusting the dumping position of the shovel to suit varying conditions. 15 75
- 15 5. A shoveling and loading machine comprising a reciprocatory frame, front and rear sprockets mounted on said frame, chains adapted to be guided by said sprockets, means associated with said sprockets to actuate said chains, a shovel pivotally supported on said chains and arranged to pass over said front and rear sprockets with said chain to be tilted downwardly and upwardly, a guide at said rear sprockets to tilt said shovel at its dumping position, and means for rocking the rear sprocket and the guides about the front sprocket for elevating and lowering the dumping position of the shovel to suit varying conditions. 30 80
- 20 6. A shoveling and loading machine comprising a reciprocatory frame, front and rear sprockets on said frame, chains adapted to be guided by said sprockets, a shovel, a bracket for said shovel pivoted rearwardly on the chains, an arm on said bracket, a guide cooperative with said arm to tilt and dump said shovel, and means for pivotally adjusting the guide and rear sprocket about the front sprocket for adjusting the dumping position of the shovel to suit varying conditions. 45 85
- 25 7. A shoveling and loading machine comprising a reciprocatory frame, front and rear sprockets on said frame, chains adapted to be guided by said sprockets, means cooperative with the rear sprockets for actuating said chains, a shovel, a bracket for said shovel pivotally supported on said chains, an arm on said bracket, a guide cooperative with said arm to tilt and dump said shovel, and means for pivotally adjusting the guide and rear sprocket about the front sprocket for adjusting vertically the dumping position of the shovel to suit varying conditions. 50 90
- 30 8. A shoveling and loading machine comprising a reciprocatory frame, front and rear sprockets on said frame, chains adapted to be guided by said sprockets, a shovel, a bracket for said shovel pivotally supported by said chains, a rearwardly extending arm on said bracket, a guide about one of said sprockets cooperative with said arm to tilt and dump said shovel, and means for pivotally adjusting the guide and rear sprocket about the front sprocket for adjusting vertically the dumping position of the shovel to suit varying conditions. 55 95
- 35 9. A shoveling and loading machine comprising a reciprocatory frame, front and rear sprockets on said frame, chains adapted to be guided by said sprockets, a shovel, a bracket for said shovel pivotally supported by said chains, a rearwardly extending arm on said bracket, a guide about one of said rear sprockets cooperative with said arm to tilt and dump said shovel, forwardly disposed pins on said bracket, a shoe on said chain upon which said pin is adapted to rest to support the thrust of the shovel when the latter is in its loading position, and means for pivotally adjusting the guide and rear sprocket about the front sprocket for adjusting vertically the dumping position of the shovel to suit varying conditions. 60 100
- 40 10. A shoveling and loading machine comprising a platform, a cylinder on said platform, a frame, a plunger cooperative with said cylinder to reciprocate said frame, front and rear sprockets on said frame, chains adapted to be guided by said sprockets, a shovel supported by said chains and adapted to be carried thereby between a forward shoveling position and a rearward dumping position, and means for rocking the rear sprocket about the front sprocket for adjusting vertically the dumping position of the shovel. 65 105
- 45 11. A shoveling and loading machine comprising a platform, a cylinder on said platform, a frame, a plunger cooperative with said cylinder and adapted to reciprocate said frame, front and rear sprockets mounted on said frame, chains adapted to be guided by said sprockets, a shovel pivotally supported on said chains and adapted to be carried thereby between a forward shoveling position and a rearward dumping position, and means for rocking the rear sprocket about the front sprocket for adjusting vertically the dumping position of the shovel. 70 110
- 50 12. A shoveling and loading machine comprising a platform, a cylinder on said platform, a frame, a plunger cooperative with said cylinder to reciprocate the frame, front and rear sprockets mounted on said frame, chains adapted to be guided by said sprockets, a shovel pivotally supported on said chains and adapted to pass over said front and rear sprockets with said chain to be tilted downwardly and upwardly, and manually adjustable means for providing piv- 75 115

- total movement of the rear sprocket about the front sprocket to enable the dumping position of the shovel to be varied to suit varying conditions.
13. A shoveling and loading machine comprising a platform, a cylinder on said platform, a frame, a plunger cooperative with said cylinder to reciprocate said frame, front and rear sprockets mounted on said frame, chains adapted to be guided by said sprockets, means to actuate said chains, a shovel pivotally supported on said chains and arranged to pass over said front and rear sprockets with said chains to be tilted downwardly and upwardly, and manually adjustable means to permit pivotal movement of the rear sprocket about the front sprocket for vertically adjusting the dumping position of the shovel to suit varying conditions.
14. A shoveling and loading machine comprising, a platform, a cylinder on said platform, a frame, a plunger cooperative with said cylinder to reciprocate said frame, front and rear sprockets mounted on said frame, chains adapted to be guided by said sprockets, means to actuate said chains, a shovel pivotally supported on said chains and arranged to pass over said front and rear sprockets with said chain to be tilted downwardly and upwardly, a guide on said rear sprockets to tilt said shovel at its dumping position, and manually adjustable means to permit pivotal movement of the rear sprocket about the front sprocket for vertically adjusting the dumping position of the shovel to suit varying conditions.
15. A shoveling and loading machine comprising a platform, a cylinder on said platform, a frame, a plunger cooperative with said cylinder to reciprocate said frame, front and rear sprockets on the frame, chains adapted to be guided by the sprockets, a shovel, a bracket for said shovel pivoted rearwardly on the chains, an arm on said bracket, a guide cooperative with said arm to tilt and dump said shovel, and manually adjustable means to provide pivotal movement of the rear sprocket about the front sprocket for adjusting the dumping position of the shovel in a vertical direction to suit varying conditions.
16. A shoveling and loading machine comprising a platform, a cylinder on said platform, a frame, a plunger cooperative with said cylinder to reciprocate the frame, front and rear sprockets on the frame, chains adapted to be guided by the sprockets, means cooperative with the sprockets for actuating the chains, a shovel, a bracket for said shovel pivotally supported on said chains, a rearwardly extending arm on the bracket, a guide about one of the sprockets cooperative with said arm to tilt and dump said shovel, and manually adjustable means to provide pivotal movement of the rear sprocket about the front sprocket for adjusting the dumping position of the shovel in a vertical direction to suit varying conditions.
17. A shoveling and loading machine comprising a platform, a cylinder on said platform, a frame, a plunger cooperative with said cylinder to reciprocate the frame, front and rear sprockets on said frame, chains adapted to be guided by the sprockets, a shovel, a bracket for said shovel pivotally supported by the chains, a rearwardly extending arm on the bracket, a guide about one of the sprockets cooperative with said arm to tilt and dump said shovel, a forwardly disposed pin on said bracket, a shoe on the chain upon which said pin is adapted to rest to support the thrust of the shovel when the latter is in its loading position, and means including a bracket and bolts to provide pivotal movement of the rear sprocket about the front sprocket for adjusting the dumping position of the shovel in a vertical direction.
18. A shoveling and loading machine comprising a reciprocating frame, front and rear sprockets on said frame, chains adapted to be guided by the sprockets, a shovel, a bracket for said shovel pivotally supported by the chains, a rearwardly extending arm on the bracket, a guide about one of the rear sprockets cooperative with said arm to tilt and dump the shovel, a forwardly disposed pin on said bracket, a shoe on said chain upon which said pin is adapted to rest to support the thrust of the shovel when the latter is in its loading position, a bracket having an arcuate slot to permit said frame to be pivoted about the front sprockets for regulating the dumping position of the shovel, and means for clamping the frame to said bracket.
19. A shoveling and loading machine comprising a reciprocating frame, front and rear sprockets mounted on said frame, chains adapted to be guided by the sprockets, a shovel supported by chains and adapted to be carried thereby between a forward shoveling position and a rearward dumping position, and means for oscillating the rear sprockets about the front sprockets to adjust the dumping position of the shovel including a guide, a bracket, a housing inclosing the sprockets, and bolts in said housing cooperative with the bracket.
20. A shoveling and loading machine comprising a reciprocating frame, front and rear sprockets mounted on the frame, chains adapted to be guided by said sprockets, a housing inclosing said sprocket and chains, a shovel, a bracket for said shovel pivotally supported by said chains, a rearwardly extending arm on said bracket, a guide about one of said rear sprockets formed integrally with said housing cooperative with said arm.

to tilt and dump said shovel, a forwardly disposed pin on said bracket, a shoe upon which said pin is adapted to rest to support the thrust of the shovel when the latter is in its loading position, and a bracket on said frame provided with clamping means co-operative with said housing to permit oscil-

lation of the rear sprockets about the front sprockets to adjust the dumping position of the shovel.

10

In testimony whereof I have signed this specification.

HAROLD I. STAGE.
